YIELDING REED MECHANISM

Carl D. Brown, Hopedale, Mass., assignor to
Draper Corporation, Hopedale, Mass., a corpora-
tion of Maine

Application October 22, 1936, Serial No. 107,049

14 Claims. (Cl. 139—188)

The present invention pertains to looms and more particularly to yielding reed mechanisms for shuttle looms.

In a loom of the type to which my invention pertains, the reed is so mounted on the reciprocating lay as to be capable of rearward movement relative thereto. Reed controlling instrumentalities permit the reed to yield rearwardly when the lay is forward and the reed is in contact with the fell of the cloth, but tend to hold the reed in its forward position when the lay is back from the fell and the shuttle is in flight. Under some conditions, it is necessary to provide greater resistance to rearward yielding of the reed when the lay is back than when it is forward, and instrumentalities intended to accomplish that result have been proposed heretofore. However, I find that such prior reed controlling instrumentalities are unsatisfactory in that, for example, they employ springs which are compressed or stretched a considerable distance each pick of the loom and which therefore break rather frequently, or they are so constructed as to require the use of large and cumbersome parts or parts which are subject to excessive wear.

It is accordingly an object of the present invention to provide, in a loom having a reciprocating lay and yielding reed as aforesaid, reed controlling instrumentalities which shall provide greater resistance to the rearward yielding of the reed when the lay is back than when the lay is in its forward position, and which instrumentalities shall not embody the above-mentioned, and other, objectionable features.

The foregoing and other objects may be conveniently accomplished by the construction illustrated on the accompanying drawings, which construction comprises the preferred embodiment of my invention. Referring to the drawings:

Fig. 1 is a view in cross-section taken approximately on line 1—1 of Fig. 3, showing the position of the parts when the lay is back from its forwardmost position;

Fig. 2 is a view similar to Fig. 1 but showing the position of the parts when the lay is in its forward position;

Fig. 3 is a view in rear elevation of a part of the lay and the reed and reed controlling instrumentalities; and

Fig. 4 is a view in front elevation of the mechanism shown on Fig. 3.

The drawings show only as much of the loom as is necessary to a complete understanding of the present invention, the parts of the loom not

shown being of any suitable usual construction. Of the conventional parts of the loom, there is shown the breast beam 1 which is a fixed part of the frame located at the front of the loom. There is also shown the lay assembly, hereinafter called the lay, which comprises lay swords 2 carrying a lay beam 3, shuttle boxes, as 4, and a reed 5. The lay reciprocates toward and from the front of the loom, which is toward and from the breast beam 1, in the usual manner. The warp sheet W feeds forwardly through the reed and as the picks of filling thread are left by the shuttle (not shown) they are beaten into the fell F of the cloth C by the reed.

The reed 5 is mounted on the reciprocating lay but is capable of rearward movement relative thereto. To this end, the reed may be mounted in a movable reed frame. In the embodiment shown on the drawings, the reed frame consists of a hand rail 6, a bottom rail 7 and end brackets 8 connecting the hand rail and bottom rail, the reed frame being pivoted on horizontal studs or bolts 9 carried by the swords materially above the plane of the cloth C. My invention particularly relates to the means for yieldingly resisting relative rearward movement of such a reed, or reed frame, when the lay is in its forward position and for firmly holding the reed against such rearward movement while the lay is back and the shuttle is in flight.

The reed controlling instrumentalities shown on the drawings comprise oppositely acting spring means exerting a net force on the reed frame which is sufficient to prevent rearward movement of the reed when the lay is back, but one of which means is intermittently actuated to temporarily decrease the net resistance to rearward movement of the reed when the lay is in its forward position. More specifically, two separate springs or sets of springs act in a direction to resist rearward movement of the reed, thus providing a strong resistance to reed movement. One set of such springs acts through bolts which are directly connected with the reed frame, while the other set of such springs acts through a movable element which engages the reed frame. The opposing spring, or springs, acts on the movable element only, such spring having little or no force when the lay is back but being stressed, to thereby partially or wholly relieve the reed frame of the pressure of the movable element, when the lay is in its forward position.

Of the bolts above referred to, the drawings show only one bolt 10 with a coiled spring 11 surrounding the same. The bolt 10 extends hori-

zontally through a hole in the lay beam, the head of the bolt engaging a plate 12 on the bottom rail 7 of the reed frame. The spring 11 is compressed between the lay beam and adjusting 5 nuts 13 on the forward end of the bolt. The spring and nut thus act on the reed frame in a direction to resist rearward movement of the latter and the resisting force may be adjusted by means of the nuts 13. A plurality of similar 10 springs and bolts, spaced at intervals along the lay, may be provided if so desired. While, as will become apparent, these springs and bolts may be omitted under some circumstances, I prefer to use them because by engaging the reed frame 15 between the ends thereof they reinforce the reed against bending. Also, the adjusting nuts 13, in conjunction with other adjusting means to be described, provide for adaptation of the mechanism to the weaving of a wide variety of fabrics.

20 The springs 11 just described may be designed to provide enough, or less than enough, resistance to rearward yielding of the reed to properly beat the picks of filling into the fell of the cloth while still permitting the reed to yield rearward- 25 ly to compensate for irregularities in the filling or in the position of the fell. The resistance provided by the springs 11 is thus materially less than is required to hold the reed firmly in place when the lay is back and the shuttle is in flight. 30 The spring means acting to oppose rearward movement of the reed accordingly includes not only the springs 11, if such are provided, but also springs such as the coiled spring 14 which preferably acts on the reed frame through the me- 35 dium of a member 15 movably mounted on the lay.

In the embodiment shown on the drawings, the spring 14 is carried by the lay, it being conveniently mounted on a rod 16 which is supported 40 by a bracket 17 on the lay sword 2. The rod may also be partially supported by the member 15, as shown. The member 15 is in the form of a lever which is pivoted to the lay sword at 18. Duplicate parts, not shown, are provided at the 45 other side of the loom. The spring 14 is compressed between the bracket 17 and the lower arm of the lever 15 and the upper arm of the latter engages behind the reed frame. As shown, the upper arm of the lever contacts a projection 19 50 formed on the end bracket 8 of the reed frame. The springs 14 being quite strong, I have thus provided means capable of holding the reed firmly in place when the lay is back and the shuttle is in flight. The springs 14 and 11, being carried 55 by the lay, are not required to stretch or compress to accommodate the reciprocating movement of the lay, and are thus under substantially constant tension whereby spring breakage is materially reduced.

60 The above mentioned spring means which opposes the action of the spring means above described in detail includes, in the embodiment shown, a coiled compression spring 20 which is intermittently stressed, to temporarily decrease 65 the net resistance to rearward movement of the reed each time the lay approaches its forward position. The spring 20 surrounds an actuating element which may be comprised of a rod 21 slidably mounted on the lay. The forward end 70 of this rod is guided by a bracket 22 on the lay beam 3 while the rearward end thereof is guided by a bearing in the lever 15. A collar 23 is adjustably secured to the rod and engages the spring 20 to compress the latter when the rod 75 is moved rearwardly. The rod 21 is normally

urged forwardly by the spring 20, the forward position being determined by engagement of the collar 23 with the bracket 22.

The rod 21 is normally in the position shown by Fig. 1 but is moved rearwardly relative to the lay to temporarily stress, or impart additional stress to, the spring 20 each time the lay moves to its forward position, Fig. 2. To this end, a stationary bunter 24 is fixed to the loom in position to engage a head 25 on the rod slightly before the lay has reached its extreme forward position. When the bunter 24 is engaged by the head 25 the rod 21 is prevented from continuing its forward movement with the lay and the rod therefore may be said to move rearwardly relative to the lay. This rearward movement compresses the spring 20 and thus causes the latter to yielding- 15 ure the lever 15 in a direction away from the reed frame. The spring 20 and its actuating parts are duplicated at the other side of the loom, the duplicate parts being not shown.

It will be apparent that, according to the proportions of the various parts and the position of the adjustable collar 23, the spring may or may not be under stress when the rod 21 is in its extreme forward position, Fig. 1. I prefer that the spring 20 be slightly stressed, i. e., compressed, when the rod is in such forward position, although this is not of any very great importance. In any event, the spring 20 when expanded is much weaker than the spring 14.

It will likewise be apparent that the effect of the spring 20 on the lever 15, when the rod 21 is moved rearwardly by the bunter, will vary according to whether, at such times, the spring 20 is stronger or weaker than the spring 14. Preferably, the nuts 13 are adjusted so that the springs 11 do not provide enough force to properly beat in the filling, and the collars 23 are adjusted so that when the lay is in its forward position the springs 20 do not quite counteract the action of the springs 14, the latter then assisting the springs 11 to beat in the filling. However, the invention contemplates adjustment of the collar 23, or the changing of spring 20, to enable the latter to move the lever 15 out of engagement with the reed frame, if so desired, in which case the nuts 13 must be adjusted to increase the stress of the springs 11. On the other hand, omission of the springs 11 can be compensated for by proper adjustment of the collar 23 or by substitution of a stronger spring 14.

It will thus be seen that I have provided in the embodiment shown relatively strong spring means, comprising springs 11 and 14 and their associated parts, for resisting rearward movement of the reed, and opposing spring means intermittently actuated to decrease the net resistance to rearward movement of the reed when the lay is in its forward position. Providing the desired variation in resistance to reed movement by oppositely acting spring means facilitates the provision of convenient adjusting means whereby the mechanism may be readily adapted to the weaving of a wide variety of fabrics. Furthermore, such oppositely acting spring means carried entirely by the lay, and the purely intermittently operating means, may be readily designed so as to require only a very slight repeated stretching or compressing of the springs, thus contributing materially to the length of time that the springs will last. The particular embodiment described in detail is further characterized by extreme simplicity in construction and operation and by a very desirable compactness of construction.

Having fully disclosed the preferred embodiment of my invention, I claim:

1. In a loom, the combination of the reciprocating lay, a reed mounted on the lay for rearward movement relative thereto, relatively strong spring means acting to resist said rearward movement of the reed, relatively weaker spring means mounted on the lay for bodily movement therewith and opposing said action of said strong spring means, and means for temporarily decreasing the net resistance of said spring means to said rearward movement of the reed each time the lay moves to its forward position.
2. In a loom, the combination of the reciprocating lay, a reed mounted on the lay for rearward movement relative thereto, relatively strong spring means acting to resist said rearward movement of the reed, relatively weaker spring means mounted on the lay for bodily movement therewith and opposing said action of said strong spring means, and means for temporarily imparting additional stress to said weaker spring means each time the lay moves to its forward position.
3. In a loom, the combination of the reciprocating lay, a reed mounted on the lay for rearward movement relative thereto, relatively strong spring means carried entirely by the lay and acting to resist said rearward movement of the reed, relatively weaker spring means carried by the lay and opposing said action of said strong spring means, and means for temporarily imparting additional stress to said weaker spring means each time the lay moves to its forward position.
4. In a loom, the combination of the reciprocating lay, a reed mounted on the lay for rearward movement relative thereto, constant-tension spring means normally acting to resist said rearward movement of the reed, relatively weaker spring means yieldingly opposing the action of the first said spring means, and means acting intermittently to temporarily impart additional stress to said weaker spring means each time the lay moves to its forward position.
5. In a loom, the combination of the reciprocating lay, a reed mounted on the lay for rearward movement relative thereto, relatively strong spring means carried by the lay and acting to resist said rearward movement of the reed, other spring means carried entirely by the lay and acting when stressed to yieldingly oppose the action of the first said spring means, and means acting intermittently to temporarily stress said other spring means each time the lay moves to its forward position.
6. In a loom, the combination of the reciprocating lay, a reed mounted on the lay for rearward movement relative thereto, constant-tension spring means normally acting to resist said rearward movement of the reed, other spring means mounted on the lay for movement therewith, said other spring means acting when stressed to yieldingly oppose the action of the first said spring means, and means acting intermittently to stress said other spring means each time the lay moves to its forward position.
7. In a loom, the combination of the reciprocating lay, a reed frame mounted on the lay for rearward movement relative thereto, a reed in said reed frame, means including a spring and a member urged by said spring into engagement with said reed frame for resisting said rearward movement of the reed frame, another spring mounted on the lay for movement therewith and acting when stressed to oppose the action of the
- first said spring on said member, and means acting intermittently to temporarily stress said other spring each time the lay moves to its forward position.
8. In a loom, the combination of the reciprocating lay, a reed frame mounted on the lay for rearward movement relative thereto, a reed in said reed frame, spring means carried entirely by the lay and acting on said reed frame to yieldingly resist said rearward movement of the latter, a member movably mounted on the lay, spring means acting to yieldingly hold said member against said reed frame to thereby further resist said rearward movement of the reed frame, other spring means acting when stressed to yieldingly urge said member away from said reed frame, and means acting intermittently to temporarily stress said other spring means each time the lay moves to its forward position.
9. In a loom, the combination of the reciprocating lay, a reed frame mounted on the lay for rearward movement relative thereto, a reed in said reed frame, spring means carried by the lay and acting on said reed frame to yieldingly resist said rearward movement of the latter, a member movably mounted on the lay, a relatively strong spring yieldingly urging said member against said reed frame to thereby further resist said rearward movement of the reed frame, a relatively weaker spring acting on said member in a direction to urge the latter away from said reed frame, and means acting intermittently to temporarily increase the force exerted by said weaker spring on said member each time the lay moves to its forward position.
10. In a loom, the combination of the reciprocating lay, a reed frame mounted on the lay for rearward movement relative thereto, a reed in said reed frame, spring means carried by the lay for yieldingly resisting said rearward movement of the reed frame, constant-tension spring means acting to further resist said rearward movement of the reed frame, and intermittently actuated means yieldingly opposing the action of said constant-tension means each time the lay moves to its forward position.
11. In a loom, the combination of the reciprocating lay, a reed frame mounted on the lay for rearward movement relative thereto, a reed in said reed frame, means including a member movably mounted on the lay and a spring urging said member into engagement with said reed frame for resisting said rearward movement of the latter, a second spring acting when stressed to urge said member away from said reed frame, an element movably mounted on the lay in engagement with said second spring, and a stationary bunter positioned to engage said element and move the same relative to the lay, to thereby stress said second spring, each time the lay moves to its forward position.
12. In a loom, the combination of the reciprocating lay, a reed frame mounted on the lay for rearward movement relative thereto, a reed in said reed frame, a member pivotally mounted on the lay and engaging behind said reed frame, a relatively strong spring acting on said member in a direction to cause the latter to resist said rearward movement of said reed frame, a relatively weaker spring carried entirely by the lay and acting on said member in a direction to urge the latter away from said reed frame, an element movably mounted on the lay for imparting additional stress to said weaker spring, and a stationary bunter positioned to engage and move

said element, to thereby temporarily impart said additional stress to said weaker spring, each time the lay moves to its forward position.

13. In a loom, the combination of the reciprocating lay, a reed frame mounted on the lay for rearward movement relative thereto, a reed in said reed frame, spring means carried by the lay and yieldingly resisting said rearward movement of said reed frame, a spring-actuated lever pivotally mounted on the lay and engaging behind said reed frame to further resist said rearward movement of the latter, an element movably mounted on the lay, a stationary bunter positioned to be engaged by said element and move the latter rearwardly relative to the lay each time the lay moves to its forward position, and a spring interposed between said element and said member for urging the latter in a direction away from said reed frame each time said element is moved as aforesaid.

14. In a loom, the combination of the recipro-

cating lay, a reed frame mounted on the lay for rearward movement relative thereto, a reed in said frame, spring means carried by the lay and yieldingly resisting said rearward movement of said reed frame, a lever pivotally mounted on the lay and engaging behind said reed frame, a spring carried by the lay and continuously acting on said lever in a direction to cause the lever to further resist said rearward movement of the reed frame, a rod slidably mounted on the lay for movement forwardly and rearwardly relative thereto, a stationary bunter positioned to be engaged by said rod for moving the latter rearwardly relative to the lay as the latter moves to its forward position, a spring surrounding said rod and acting when stressed to urge said lever away from said reed frame, and a connection between said rod and the last said spring whereby the latter is stressed each time the rod is moved rearwardly as aforesaid.

20

CARL D. BROWN.
